UNITED STATES PATENT OFFICE.

WILLARD H. HEATH, OF SPOKANE, WASHINGTON.

VALVE GRINDER.

1,414,358.

Specification of Letters Patent.

Patented May 2, 1922.

Application filed November 5, 1919. Serial No. 385,834.

To all whom it may concern:

Be it known that I, WILLARD H. HEATH, a citizen of the United States, residing at Spokane, in Spokane County and State of Washington, have invented certain new and useful Improvements in Valve Grinders, of which the following is a specification.

The present invention relates to an improved portable valve-grinding tool adapted for grinding the valves and valve seat of internal combustion engines, and while the invention is especially applicable for use in connection with the grinding of valves of Ford automobiles, or rather, for grinding the valves of the Ford motors, yet it is capable of use on any type of engine involving a construction wherein the top of the engine is removable to gain access to the valves and their seats.

20 The subject matter of the invention is a hand operated tool that is capable of compact storing, and which occupies but comparatively small space for storing when not in use, and which may be assembled and 25 placed in operative position for grinding the valves and their seats with facility, and with equal dispatch and convenience may be disassembled, and stored away.

The invention consists in certain novel 30 combinations and arrangements of parts as hereinafter described and claimed and as illustrated in the drawings wherein the physical embodiment of the invention is constructed according to the best mode so far 35 devised for the practical application of the principles of the invention.

Figure 1 is a sectional view of so much of an internal combustion engine, showing a valve and its seat, as is necessary to illustrate the application of the invention.

Figure 2 is a sectional view of the handle of the tool showing a spring stored therein, when not in use.

In order that the invention may be readily 45 understood the upper part of the engine, of the internal combustion type, is indicated at 1 having the valve seat 2 for the valve 3, which is supported by its stem 4 in the bearing 5, and the valve head is fashioned with 50 a pair of diametrically disposed sockets 6, 7, in its upper surface, which are bored therein to adapt it for use with the grinding tool of the invention.

The operating tool comprises essentially 55 the handle 8 fashioned preferably of metal

with a spherical head 9, and the lower end of the handle has a pair of pins 10 projecting therebelow complementary with and adapted to engage in the two sockets 6 and 7 provided in the upper face of the valve. 60 The handle is bored out to provide a recess 11 in which the spring 12 is stored, and retained by the cotter pin 13, when not in use, but the head possesses sufficient weight to counterbalance the movement of the 65 grinding tool as the latter is oscillated between the two hands of the operator. Thus, to oscillate the tool, the head is held between the palms of the hands, the tool being erect or vertical, and the hands being also held in 70 vertical planes, while the hands are alternately reciprocated horizontally, which action gives the tool an oscillatory movement in a horizontal plane, the tool turning first in one direction and then in the reverse 75 direction.

The tool is supported at its lower end by the pin and socket connection with the valve, and in Figure 1 it will be seen that the valve is resiliently supported above its seat by the 80 spring 12 which has been removed from its pocket 11 in the handle, and interposed between the under face of the valve head and the valve-stem bearing 5.

From above, the tool is supported by 85 means of the inverted L-shape bar 14, threaded at 15 into one of the threaded holes in the engine casing which receives a bolt to secure the top on the engine. After the securing bolts and top have been removed from the 90 top of the engine, this bar is threaded into one of the bolt holes, as a temporary support for the tool, and the bar supports the tool through the instrumentality of the spring 95 pressed bearing pin 16 passed vertically through the horizontally disposed eye 17 formed as a flat boss on the short arm 18 of the supporting bar. The pin is fashioned with a lower head 19 of conical shape to fit into the socket 20 of the bearing block 21 seated in the upper end of the tool handle 9, and between the conical head of the pin and the boss 17 a spring 22 is interposed.

As above specified it will be seen that the tool handle is resiliently supported above 105 and below by the respective springs 22 and 12 thus permitting a vertical reciprocation, to a limited degree, of the tool which enables the valve head to be lifted from its seat by the spring 12 in order that the valve, when 110

lifted, will release the abrasive used in grinding and permit it to fall from the valve seat as the grinding progresses.

With the parts in the position shown in Figure 1, the two hands, spread flat and held vertically, are applied at the sides of the tool head 9 and an alternating reciprocating motion of the hands with a rubbing movement on the tool handle causes the tool and valve to oscillate, with the valve stem valve and conical bearing head 19 as the center of movement, and the continuous oscillation of the tool and valve on this axis effects the grinding of the valve in its seat. The tendency of the spring 12, which has a tension superior to that of the spring 22, is to lift the valve from its seat, and therefore the hands of the operator, by a downward pressure on the head 9, hold the valve on its seat during the grinding movement, and during this movement the relative position of the valve in its seat is frequently changed in order to avoid grinding these parts unevenly. The grinding and re-adjusting of the valve is continued until desired close or tight fit is secured between the valve and its

seat, and then the parts may be disassembled quickly and with facility by lifting the tool against the tension of the spring 22 to remove the two retaining pins 10 from the valve, and then the tool is withdrawn from its conical head. The spring 12 is withdrawn from the valve stem and placed in its pocket in the tool head and the cotter pin 13 inserted to retain it, after which the supporting bar 14 is turned or backed out of the bolt hole in the engine casing, and the valve may be replaced and top of the engine again secured in place.

What I claim is—

The combination in a hand operated grinding tool of an oscillatable handle and retaining pins on said handle to engage sockets in a valve, a resilient support for the valve, a supporting post having a bearing, a pin in the bearing and provided with a bearing to engage said handle, and a spring between the post bearing and pin bearing.

In testimony whereof I affix my signature. 50

WILLARD H. HEATH.
